CLAIM

The ornamental design for the monitor, as shown and described.

DESCRIPTION

FIG. 1 is a front elevational view of the monitor; FIG. 2 is a rear elevational view of the monitor; FIG. 3 is a front perspective view of the monitor; FIG. 4 is a rear perspective view of the monitor; FIG. 5 is a right elevational view of the monitor; FIG. 6 is a left elevational view of the monitor; FIG. 7 is a top plan view of the monitor; and, FIG. 8 is a bottom plan view of the monitor. Broken lines shown in the drawings illustrate portions of the monitor, and form no part of the claimed design.
